Des. 206,071
Patented Oct. 25, 1966

206,071

ELECTRICAL HANGING ORNAMENT OR SIMILAR ARTICLE

Jack Burnbaum, 451 D St., Newton, Mass.

Filed June 11, 1965, Ser. No. 85,772

Term of patent 14 years

(Cl. D29—1)

FIG. I

FIG. 2

FIG. 3

FIG. 1 is a side elevational view of an electrical hanging ornament showing my new design;

FIG. 2 is a top plan view, and

FIG. 3 is a bottom plan view thereof.

I claim:

The ornamental design for an electrical hanging ornament, or similar article, substantially as shown.
